DESIGN FOR A BURIAL CASE

James L. Grissinger, Marion, Ohio, assignor to
The Marion Steel Body Company, Marion,
Ohio, a corporation of Ohio

Application September 25, 1935, Serial No. 58,710

Term of patent 7 years

To all whom it may concern:

Be it known that I, James L. Grissinger, a citizen of the United States, residing at Marion, in the county of Marion and State of Ohio, have invented a new, original, and ornamental Design for a Burial Case, of which the following is a specification, reference being had to the accompanying drawing, forming part thereof, wherein Fig. 1 is a side elevation and Fig. 2 is an end elevation of a burial case showing my new design.

I claim:—

The ornamental design for a burial case, substantially as shown.

JAMES L. GRISSINGER.
